UNITED STATES PATENT OFFICE.

FRANCIS KARR, OF HOLLAND, MICHIGAN.

SPRING BED-BOTTOM.

SPECIFICATION forming part of Letters Patent No. 774,670, dated November 8, 1904.

Application filed November 10, 1903. Serial No. 180,622. (No model.)

To all whom it may concern:

Be it known that I, FRANCIS KARR, a citizen of the United States, residing at Holland, in the county of Ottawa and State of Michigan, have invented certain new and useful Improvements in Spring Bed-Bottoms, of which the following is a specification.

My invention relates to improvements in woven-wire spring bed-bottoms; and its objects are, first, to provide an easily-applicable center support for the woven-wire fabric, and, second, to provide a support that may be easily adjusted longitudinally of the woven-wire fabric. I attain these objects by the mechanism illustrated in the accompanying drawings, in which—

Figure 1 is a perspective of a spring-frame with the woven-wire fabric removed to show the manner of applying the supports. Fig. 2 is a perspective of one section of the support. Fig. 3 is a side view of a woven-wire spring bed-bottom with the support in place, and Fig. 4 is the same without the support.

Similar letters refer to similar parts throughout the several views.

A A represent the end rails, and A' A' represent the side rails, of the frame that supports the woven-wire fabric F, the ends of the fabric being secured to the end rails A A, as indicated in Figs. 3 and 4.

The support I aim to provide consists of a series of wire yokes bent to form the upwardly-projecting cross-rods C', bent to form the vertical supports c, so situated that the ends c' will project some distance, so that when placed in the bed-bottom these ends will overlap, as indicated in Fig. 1, forming a practically continuous support, and again bent back at the point of connecting with the helical springs B to form a proper connection with the ends of these springs, whence the arms C C project back and are provided with hooks c''. In the more simple construction I place two of these yokes in each support and connect the hooks c'' directly with the hooks d on the grip-wires D and place the two helical springs B between them in such a manner that any weight upon the top of the fabric will press down upon the cross-bars C', forc-

ing the fabric F practically to the position of the dotted lines in Fig. 3, which will cause the helical springs B to expand longitudinally and will utilize the increased tension of the spring to hold the fabric and its load up to a comfortable position, instead of allowing them to drop down below the level to the position shown by the dotted lines in Fig. 4 or lower.

The grip-wires D are passed around the end rails A and the ends d'' hooked around the upper wire, as indicated, so that they may be easily adjusted and cannot be drawn off of the rails by the increased tension of the springs B.

For the purpose of making this support adjustable—that is, so that the distance between the cross-bars C' may be varied—I interpose links E, either between the hooks c'' and d, as in Fig. 2, to allow only the length of the helical springs B between the yokes or between the ends of the helical springs B and the standard c, as in Fig. 3, to increase the distance between the bars C', or they may be placed with only one pair of links in each place to change the position of the center of the bed-bottom, or, if desired, the position of the links and the spring may be interchanged.

Having thus fully described my invention, what I claim as new, and desire to secure by Letters Patent of the United States, is—

1. In combination with the side rails, end rails, and fabric of a spring bed-bottom; a support consisting of cross-bars, engaging the fabric from below, bent and extending downward, then bent and extending longitudinally of the bed, and intervening springs; the said support secured to the end rails, substantially as and for the purpose set forth.

2. In combination with a spring bed-bottom, the end rails, side rails, and fabric thereof; supporting-bodies, bearing crosswise of the lower side of the fabric, bent and extending downward, bent again and extending longitudinally of the bed, and secured to the end rails of the bed-bottom, and intervening springs in the longitudinal construction of said supports, substantially as and for the purpose set forth.

3. In combination with a spring bed-bottom, the end rails, side rails and fabric there-

of, wires forming lateral supporting-bodies bent and extending downward then bent and extending longitudinally of the bed, and links, attached to the end rails of the bed-bottom, 5 and intervening springs in the longitudinal construction of said supports, substantially as and for the purpose set forth.

Signed at Grand Rapids, Michigan, October 12, 1903.

FRANCIS KARR.

In presence of—

**I. J. CILLEY,
C. V. CILLEY.**
